FIG. 1 is an exploded perspective view of a bullet novelty caddy showing the new design;

FIG. 2 is another exploded perspective view thereof;

FIG. 3 is a front view thereof;

FIG. 4 is a rear view thereof;

FIG. 5 is a detached bullet case end cap view thereof;

FIG. 6 is a bullet case closed end view thereof;

FIG. 7 is a side view thereof, the opposite side view being a mirror image;

FIG. 8 is a cutaway side view thereof, the opposite cutaway side view being a mirror image;

FIG. 9 is a front view showing the design of FIG. 1 in an environment of use; and,

FIG. 10 is a front view showing the design of FIG. 1 in an alternate environment of use.

The broken lines in FIGS. 9-10 illustrate environmental structure and form no part of the claimed design.
